C. O. Crosby
Papering Pins

No 8,007. Fig. 1.

Fig. 2. Patented April 1, 1851.

UNITED STATES PATENT OFFICE.

C. O. CROSBY, OF NEW HAVEN, CONNECTICUT.

MACHINE FOR STICKING PINS ON PAPER.

Specification of Letters Patent No. 8,007, dated April 1, 1851.

To all whom it may concern:

Be it known that I, CHAUNCEY O. CROSBY, of New Haven, in the county of New Haven, in the State of Connecticut, have invented 5 a new and useful machine for sticking pins crosswise of narrow fillets or ribbons of paper in order for and preparatory to winding the fillet endwise, and so rolling, coiling, or wrapping it together in that direction 10 into compact body by consecutive and successive operations of the same machine.

The nature of this machine is to receive the pins in a promiscuous mass,—that is, heads and points lying in all directions irregularly,—and reducing them to order, and bringing them forward from the “shoe” 15 through a feeding channel to a “separator,” which drops them separately,—one by one, at regular intervals of time, into a proper 20 channel before the punch, which thrusts forward at corresponding intervals, and at each thrust shoves a pin, point forward, across the face, or periphery of the large crimping roller, which carries the fillet paper,—which 25 has just passed under the upper or smaller crimping roller, the two projecting ribs around which have depressed two longitudinal crimps of the fillet into the two channels in the face of the large one and the 30 crimps in the fillet remain in their channels to the sticking point,—or where the pin, being thrust across the face of the large crimping roller, pierces the two crimps and thus 35 is stuck, or attached to the fillet,—which 40 still moves forward with the face of the large crimping wheel or roller, by an intermitting movement,—standing still a moment at the sticking of each pin, and progressing in the times between the sticking of each, 45 to the place where the fillet, with the pins inserted in it, is coiled, or wound up, into compact body, or bodies of any convenient size, and by any of the devices which are common to machinists:—though I prefer to move the revolving coil by the moving face 50 of the crimping-wheel or roller which will always have the proper superficial speed of motion.

The pins being stuck at right angles or 55 transversely across both the fillet and the longitudinal crimps or ridges in it, and their bodies lying parallel to the axis of the coil, will of course present their heads on the plane (or perhaps sometimes a little convex

or conical) face or faces of the coil, on one 55 or both edges (as the case may be) of the fillet, whether it may be rolled up, coiled or wrapped together in the foregoing manner, or in other regular ways.

The novelty of my invention consists not 60 in sticking or inserting the pins through two parallel ridges, crimps, or folds of paper raised crosswise of the broad sheet,—the length of the pin lying lengthwise of the sheet,—for this is old and well known,— 65 and the only method known to me;—but mine is a new and reversed order having the crimps lengthwise and the pins crosswise, not of a sheet,—but a narrow ribbon or fillet of paper, not necessarily much wider than 70 the length of a pin of such size as is intended to be stuck in it:—And by the old modes the pins and their heads are altogether enfolded into the parcel, and inaccessible without unfolding it; and the sheets are folded 75 endwise of the pins from both the ends of the sheet to its center, and this folding up has been hitherto performed by hand. But by my improved machine and method, the fillet and pins are so combined as aforesaid for 80 coiling, and coiled into compact bodies or rolls, so rendering them much more conveniently accessible for use in the toilet,—for dress-makers,—and for all the various purposes for which pins are used. And my ma- 85 chine is fitted to work by water or other power, while other sticking machines hitherto have not been successfully moved by other than hand power, owing to their fickleness and uncertainty of supply and distribution of the pins, and to their liability to obstructions by trifling want of straightness, or other small defects in them,—which obstructions and interruptions are in a great 90 measure obviated by my separators, and 95 other improved arrangements hereinafter described.

To enable others skilled in machinery for sticking or papering pins, to make and use this machine, I now proceed to describe the 100 parts, construction and operation thereof.

In the sectional drawings hereto annexed and forming a part of this description—Figure 1, represents a perpendicular view or plan of the machine, in which A, A, show 105 the two plates or sides of the frame; and B, shows one of the four studs which bind the frame together:—the principal parts I make

of cast iron,—the frame is about two feet high and two feet wide, and about 1 foot deep, exclusive of the high post, which stands about two feet in the rear of the principal frame, marked E.

- 5   *c, c, c, c,* represent braces to sustain the high post, and connect it to the frame;—in this, or other suitable frame the principal moving parts are,—a main shaft F, with 10 cams and pulleys on it;—the smallest cam is placed at *g*, and gives two motions to a lever and urger, or lever with elbow in it, shown at *i, i*, in Fig. 3 which moves a dog *e*, which acts upon a large ratchet-wheel H, H, 15 in front of the machine, and moves it forward two notches for each revolution of F, the main shaft;—in this large ratchet wheel it is proper to have about 288 teeth or notches, or as many, or a few more, than the 20 number of pins generally stuck in what is called a paper of pins, and for that number the wheel may be about 20 inches diameter,—but these numbers and dimensions may be varied at discretion. The wheel is, by the 25 dog, made to revolve with an intermitting motion,—and while it rests, a pin is stuck—it then moves forward one notch and rests, and another pin is stuck, and so on in like manner. On the shaft S, of the ratchet- 30 wheel is the large crimping wheel J, which is about the same diameter as the ratchet-wheel, and about one inch thick, or broad on its face or periphery, having two channels turned around it in its face, as at *o, o*, 35 of the form of a transverse section of the fillet after it is suitably crimped. Above or upon this large crimping wheel is placed a smaller one of like breadth of face, and having two projections around it to match the 40 depressions in the large one—the small roller is marked K, in Figs. 1 and 3. The fillet is crimped by running between these wheels as rollers, moderately pressed together, in a lengthwise direction.
- 45   When the first end of the fillet is entered between the crimping rollers at K, it passes onward and the ridges of paper are pressed into the channels of the large wheel continuously, and remain and pass on with the 50 wheel to the place where the pin is stuck;—at which place the pin is thrust forward from the channel into which it had been dropped by the separator,—and being thrust forward across, and close in contact 55 with, the face of the channeled crimping wheel, and under the main breadth of the fillet, while its crimps are depressed, and the pin pierces through the bases of the crimps or ridges and so is stuck.
- 60   In this machine I have no need of “clamps,” “bars,” nor “jaws” to open and shut to form the crimped ridges and to hold the paper while the pins are inserted,—as have been needed and used heretofore in all 65 other kinds of pin-sticking machines;—but

my crimping wheels or rollers, before described, press only one point at a time, which is continually moving lengthwise,—or the fillet by moving past this point forms the lines of crimped ridges. It should be further known, that the greatest pressure between the rollers should be on the middle part of the fillet, between the two ridges,—for if otherwise, it were to be pressed and holden by its edges, the raising of the ridges might split and tear the paper.

To describe more particularly the feeding parts and movements of this machine,—by which the pins are reduced to order, and brought forward through the feed channel to the separator, and by this to the place where they are dropped for sticking,—I will describe the parts and their uses.

The long conical rollers R, R, extend backward and upward to the high post E, and are geared together at their upper and largest ends at X, X, and one of them has a neck bearing extending back, beyond the post, to receive a pulley by which both are moved:—these rollers may vary in dimensions,—but I make them about 2 feet long and from $1\frac{1}{2}$ to 2 inches diameter at their longest ends,—and about one half or three-eighths of an inch at their smallest ends,—with straight sides,—or regularly tapered from end to end,—and set at a small distance apart on their inner sides—but little more than the diameter of the pin-wire, but not far enough to permit the heads of the pins to fall through between them;—they must revolve upward upon their inner sides, tending to lift the pins, and have a moderate motion from the pulley u, u. The elevation of these rollers may vary considerably, depending on the speed at which they revolve,—and may be between 15° and 25° from horizontal, so that pins thrown promiscuously upon the trough-like depression between them at the higher ends,—being agitated by the revolving rollers, the wire or body of them will successively fall through the free space between them, and hanging by their heads, will descend through the whole length of the channel.

I prefer the conical form of feeding rollers for several reasons as being much better suited to this use than cylindric rollers would be, because I want a diminishing velocity in the descent of the column of pins in the feed channels,—which is the free space or opening between the rollers,—and although different degrees of elevation will produce different degrees of rapidity in the descent of the column, yet it will be accelerated or retarded alike in its whole length; and increased rotary velocity of cylindric rollers will also increase the velocity of descent,—and still in like manner uniformly—but the superficial rotary velocity of cones diminishes from the largest to the smallest

ends,—and at any suitable elevation, will cause the upper part of the column to advance faster than the lower end of it, tending thereby, naturally, and of its own accord to bring the pins in the column into close order at its lower end,—which it is desirable and beneficial to do in order that the separator may be sure to have its regular supply;—and to do this without too much pressure on the lowest pins of the column—for if they are too much crowded anywhere in the lower part of the column, some of them will rise up out of their regular rank in the column and produce disorder.

It is also desirable and beneficial to have a wider and deeper trough or depression between the rollers at their upper ends, where the pins are first fed in, or laid on in a promiscuous manner,—and there let as many as will take their orderly position, and the whole, whether reduced to order or not should pass off descendingly, as soon as may be, to give place to a new supply of feed:—and it is desirable also that the trough-like depression between the rollers should be narrower and shallower below, in order more conveniently, to throw off the unarranged and surplus pins, laterally over one or both of the cones;—and the greater part of such surplus will throw itself off by this means, where the cones are small. All these beneficial results are obtained (and more might be named if necessary) by using the conical form of rollers, which would not be as well obtained by using cylindric ones;—unless I were to arrange several pairs of them in succession,—of different diameters,—and geared to revolve at different rates of speed,—and lapping like steps, one pair above another.

T. W. Harvey's cylindric rollers may answer his purpose well enough "for arranging screw-blanks and other similar articles,"—which have heads but no sharp points,—because such articles can be fenced in and retained within proper or assigned limits,—but pins are not easily so restrained because their sharp points will enter, wedge-like under almost any fences which will permit the free motion of the rollers,—especially when the motion of the rollers tends to draw the points under the fence or fences, and by so doing the pins are liable to lodge, and make obstructions to the feed,—which any articles not having sharp points would not do. The upper ends of my cones form a depression between them large enough to form all the "hopper" I need, and I use nothing like fences.

At the lower ends of the cones, or the lower end of the feeding channel and extending from that point near to the punch channel, where the pins are dropped for sticking, and inclining in the same direction as the feed roller, but nearer perpendicular,

I place my "screw termination" or "screw separator," which is marked *a*, and *b*, in Figs. 1 and 3, and consists of a screw *a*, much resembling a wood-screw, which has a sharp knife-like thread, especially at its upper end, and the channel between its threads should be cut deep as compared with the body and thread remaining;—yet not so deep and broad as to permit the head of a pin to pass through it. This screw is set a few degrees from perpendicular, inclining toward the feed channel, and made to revolve close to a small stud of brass or steel, *b*,—the upper and outer corner of which stud ranges a little forward of its nearest approximation to the screw,—this screw and stud, or the spaces between them, connect—or form a continuation and termination of the feed-channel, and although its first or upper thread, obstructs and prevents the decent of the column of pins above it, when the screw is not revolving,—yet when it is revolving, it will take one pin, and only one (if it is single threaded) at each revolution, carrying and holding as many pins as there are threads in its length, and depositing them regularly as they are required to be inserted or stuck; and though the train of calculation may be varied like clock-work, at the discretion of the machinist, yet each train must be consistent with itself, and can be so, because the separator controls the number and times of delivery of the pins.

I have arranged this machine to stick two pins at each turn of the main shaft, and as the screw is single threaded, it revolves twice for each turn of it, and as I use a single punch to thrust in the pins, it must act twice for one of the main shaft,—and the large ratchet wheel and the crimping wheel must be moved twice, and rest twice in the same time;—and in like manner, differing according to different calculations—which may be easily made and equally good.

I find it best to cut off the thread of the screw, leaving only its body or stem for about half an inch at its upper and lower ends, so that the pin (especially its head end) may fall a little way by its own gravity from the feed channel into the separator, and also from the separator into the punch-channel, because the pins hang so that the points advance a little forward of the head ends in both of these places.

The upper end of the separator should be set a little backward and under the lower ends of the conical rollers,—and the screw is made to revolve (outward, on the side near the stud) by a bevel gear, *f*, on the main shaft *F*, which connects with another bevel gear *d*, on a shaft inclined downward, extending under the table,—showing, by dotted lines the place of a pair of small bevel gears, one of which is on the stem or shaft of the screw separator;—the screw and its

gearing are partially shown in side elevation Fig. 2 at *a* and *b*—and also in front elevation Fig. 3 at *b* and *a*.

The main shaft *F*, has on it the large side-
5 cam *M*, which gives two motions to a turn, to the lever *P*, and thence moves the thrusting punch which slides between the plates at *n* in the channel where the pin is dropped for sticking; this punch has an
10 endwise motion full equal to three-fourths of the length of a pin. The main shaft has also upon it a cam *g*, shown by dotted lines behind the main pulleys, which gives two motions to a turn, to a bent lever or
15 elbow mark *i*, *i*, which moves the dog, which moves forward the ratchet wheel as before described. The main shaft has also upon it the pulleys *s*, *s*, which by a band, drives the under shaft *D*,—which shaft extends back
20 to and by the high post *E*,—and on the back end of *D*, is a pulley which bands upward to pulley *V*, and drives the conical feed rollers *R*, *R*, before described.

To wind up the fillet, after it is stuck or
25 set with the pins—it is carried onward by the large crimping roller, beyond the sticking point, or place of insertion, to any convenient place on the periphery of it, where a small shaft or spindle may be laid across
30 the face of this roller, and the weight of the coiling spindle resting upon the face of the roller,—the first end of the fillet being slightly attached to the spindle, it will revolve by its contact with the face of this
35 crimping roller, and so roll or coil the fillet into a compact body as fast as it is stuck and brought forward;—and the movement of the face of this roller is always right for this purpose, if there is no slipping at the
40 place of contact:—it is obvious that the coiling spindle must be so hung as to permit it to rise from the roller as the coil accumulates, and its radius of course increases.

With this machine it may often be de-
45 sirable to wind up the coils in a much larger body than the contents of a common paper of pins, with a view to re-rolling them afterwards;—by that means it can be left at work for considerable time without personal
50 attendance, for it can be worked by water or other power as hereinbefore suggested.

There is represented in Fig. 3, as seen at *L*, a small plain hand roller to hold the fillet down to the large crimping roller, at, or
55 very near the place where the pin is being inserted, this small roller is nearly if not altogether useless, and I generally leave it off.

In the machine which I have now fully and exactly described for sticking pins
60 crosswise of narrow fillets of paper, to prepare it when so stuck, for winding,—and winding the same into coils,—there are several parts which are common, or such

as have been used by others—which I do not claim separately nor in other combinations. 65

I do not claim the upper feeding channel, or inclined conductors when made of straight bars,—nor cylinders with parallel sides, which have been used for conducting wood screws and similar headed articles, nor the downward curved conductors, nor any other feeding channels, unless they are combined with the conical form of rollers, or the separator.

I do not claim the crimps, nor any peculiarity in inserting the pins through them, if made crosswise of the sheet and the pins inserted lengthwise of it,—and not crosswise of both the crimps and fillet, or ridges raised in it. 75

I do not claim nor use any kind of crimping “bars,” “jaws,” or “clamps,” as they have been heretofore used. And generally I wish it to be distinctly understood that I do not limit myself to the precise form or arrangement of parts, nor the particular devices for moving them:—for these may be much varied without changing the principle of my invention as set forth;—nor do I limit myself to the single process of inserting only one pin at once, on only one edge of the fillet, for on the same principles, with only circumstantial variations of the machinery I can insert several pins at once on the same edge of the fillet,—or on both edges of 90 it;—and other similar variations can be made by any competent machinist without any essential or substantial variation from the character of my invention, as herein described and set forth. 95

1. I do claim the conical form of rollers to constitute my feeding channel for arranging the pins and moving them forward in the channel, with the most suitably decreasing rates of descending velocity as 100 herein described.

2. I do claim also as my improvement and invention, and desire to secure by Letters Patent, the combination of the parts and the adaptation of my machine for feeding the pins, separating and delivering them, crimping the fillet, and sticking the pins crosswise of such fillet and finally rolling the fillet into a coil, substantially in the manner described. 110

3. I claim also the screw separator as described, placed in the feeding channel, to restrain the natural descent of the column of pins, so that they may be delivered as fast, and no faster than they are required 120 for sticking, substantially as herein described and set forth.

C. O. CROSBY.
